UNITED STATES PATENT OFFICE.

JOHN A. CHRYSANDER, OF NEW YORK, N. Y.

PEN CLEANER.

Application filed October 1, 1925. Serial No. 59,860.

This invention relates to pen cleaners and has for an object to provide an improved construction wherein means are provided for readily wiping a lump of ink from the end 5 of a pen and also for cleaning and polishing a pen.

Another object of the invention is to provide cleaning means for a pen which will act also as a blotter.

10 A further object of the invention, more specifically, is to provide a series of sheets of paper of different qualities arranged in groups with certain groups projecting above the others so that the pen may be cleaned 15 by the projecting groups as it is drawn thereover or blotted and polished by being inserted between any two of the sheets.

In the accompanying drawing—

20 Figure 1 is a perspective view of a pen cleaner disclosing an embodiment of the invention.

Figure 2 is a sectional view through Figure 1, on line 2—2.

25 It is well known that writing pens become rusty and also clogged with dust and dirt during use and different means have been provided heretofore for eliminating these objections as far as possible. In the present invention, means have been provided for eliminating these objections and 30 also presenting desirable features for removing objectionable objects from the pen point or for causing the pen point to be cleaned and polished without injuring the parts thereof.

35 In the accompanying drawing, an embodiment of the invention is shown which is preferably arranged in a suitable container. 1. The device consists of a plurality of series of sheets of paper 2 and between these series is arranged a second series of paper 3 which projects above the series of sheets 2

so as to present shoulders 4 over which the pen 5 is adapted to be drawn when it is desired to remove a hard lump of ink or other 45 matter therefrom. If it is desired to blot or remove the ink from the pen, the same is moved downwardly vertically when the parts are positioned as shown in Figure 2 and the pen point caused to enter between 50 certain leaves in the sections 3. When it is desired to both clean and polish the pen point, the same is inserted into any of the sections of group 2 and is moved up and down slightly whereby the pen will be 55 cleaned and in a certain sense burnished so as to act in an efficient manner. Preferably, the sheets of paper 2 may be of any desired kind, as for instance, the same quality as ordinary writing paper while the sheets in 60 the series or sections 3 preferably have a more absorbent quality, as for instance, a rather hard or tight blotting paper. In addition to cleaning and polishing as just described, the device may be used to support 65 the pen by allowing the same to rest thereon in any desired manner or by having the pen 5 inserted between any of the sheets of either series.

70 What I claim is:—

1. A cleaner for writing pens, comprising a plurality of groups or series of sheets of paper, each alternate group projecting above the next adjacent group so as to present 75 wiping shoulders.

2. A cleaner for writing pens, comprising a body formed of a series of sets of sheets of paper acting to clean and polish a pen, and a plurality of sets of sheets of paper acting to clean and blot the pen, said second sets of 80 sheets being arranged in spaced groups and dividing the first sets of sheets.

JOHN A. CHRYSANDER.
